[57] CLAIM

The ornamental design for a telephone enclosure, as shown and described.

DESCRIPTION

FIG. 1 is a perspective view of a telephone enclosure showing our new design, the broken-line showing of the support post being for illustrative purposes and forming no part of the claimed design;

FIG. 2 is a front elevational view thereof;

FIG. 3 is a top plan view thereof;

FIG. 4 is a left side elevational view thereof, the right side being a mirror image; and,

FIG. 5 is a rear elevational view thereof.

FIG. 1

FIG. 2

FIG. 3

FIG. 4

FIG. 5
